UNITED STATES PATENT OFFICE.

JAMES M. G. BEARD, OF FRUITA, COLORADO.

DESIGN FOR A STATIONARY PLATE FOR STATIC MACHINES.

SPECIFICATION forming part of Design No. 34,763, dated July 9, 1901.

Application filed June 4, 1901. Serial No. 63,168. Term of patent 14 years.

To all whom it may concern:

Be it known that I, JAMES M. G. BEARD, a citizen of the United States, and a resident of Fruita, in the county of Mesa and State of Colorado, have invented and produced a new and original Design for a Stationary Plate for Static Machines, of which the following is a specification, reference being had to the accompanying drawing, forming a part thereof, which represents a perspective view of a stationary plate for static machines embodying my design.

The design as an entirety comprises the curved marginal edge *a*, of approximately semicircular form, and the straight marginal edge *b*, opposite the edge *a*, such straight marginal edge presenting a centrally-located concave recess *b'*. At the lower portion of the

plate appears an outwardly-projected extension *c*. 20

The leading feature of the design is the approximately semicircular curved edge *a* and the oppositely-disposed straight edge *b*.

Having thus described my invention, what I claim as new, and desire to secure by Letters Patent, is—

The design for a stationary plate for static machines, as herein shown and described.

In testimony whereof I have signed my name to this specification in the presence of two subscribing witnesses.

JAMES M. G. BEARD.

Witnesses:

JOHN G. BEARD,
R. B. PORTER.
